(57) **CLAIM**

The ornamental design for a portion of an off-highway truck, as shown and described.

DESCRIPTION

FIG. 1 is a front view of a portion of an off-highway truck, showing our new design;

FIG. 2 is a right view thereof;

FIG. 3 is a back view thereof;

FIG. 4 is a left view thereof;

FIG. 5 is a top view thereof;

FIG. 6 is a left, front perspective view thereof; and,

FIG. 7 is a right, front perspective view thereof.

The bottom view forms no part of the claimed design.

The elements depicted in dashed lines form no part of the ornamental design.
